UNITED STATES PATENT OFFICE.

EDMUND TWEEDY, OF DANBURY, CONNECTICUT, AND GEORGE YULE, OF NEWARK, NEW JERSEY.

HAT-ROUNDING MACHINE.

SPECIFICATION forming part of Letters Patent No. 330,441, dated November 17, 1885.

Application filed March 30, 1885. Serial No. 160,607. (No model.)

To all whom it may concern:

Be it known that we, EDMUND TWEEDY and GEORGE YULE, citizens of the United States, residing, respectively, in Danbury and Newark, in the counties of Fairfield and Essex and States of Connecticut and New Jersey, have invented certain new and useful Improvements in Hat-Rounding Machines, fully described and represented in the following specification and the accompanying drawings, forming a part of the same.

This invention consists in the combination, with a pair of rotary cutters, of a yielding feeding-disk affixed directly to one of the cutters, and adapted to grasp the hat-brim by frictional contact therewith, and to draw the same continuously into contact with the cutting-edges.

It also consists in the combination, with the rotary cutters, of an adjustable gage applied to the band of the hat, and in various means for pressing the hat-crown against such gage and for varying the width of the brim at different points.

It also consists in certain details of construction described and shown herein.

In the drawings annexed, Figure 1 is a side elevation of a machine embodying this invention. Fig. 2 is a plan of the same, taken in section on the line $x-x$ in Fig. 1, the pressing-roller not being shown in section, and the upper cutter and its driving gear-wheel being omitted from the view, and the hat-brim being shown in dotted lines to avoid obscuring the parts beneath. Fig. 3 is a front elevation, and Fig. 4 a plan, of the entire machine, with the latter shown in section, of the hat-crown similar to that in Fig. 2. Fig. 5 is a plan of the hat brim and crown with the gage applied thereto at right angles to the position shown in Fig. 4. Fig. 6 is a front view of the cutters, enlarged, with the feeding-disk shown as an eccentric sliding plate. Fig. 7 is a vertical section of the same on line $z-z$ in Fig. 6, with

a thumb-nut for clamping the star-shaped spring. Fig. 8 is a side view, and Fig. 9 a plan, of a hat having an auxiliary band applied to the crown to vary the action of the gage; and Fig. 10 is a view of the upper cutter pressing the hat-brim upon a rubber collar,

the latter being shown in section with the hub of the lower cutter to which it is applied.

In Figs. 1, 2, 3, 4, and 10, F is the frame of the machine, sustaining the lower and upper shafts, A and C, which project from the front of the frame and carry rotary cutters a c , operating together as shears to trim off the edge of the hat-brim when properly presented thereto. The bearings for the shaft C are connected by a tie-bar, C', the rear bearing being pivoted in the frame at f, and the front bearing, r', and upper cutter being vertically adjustable by means of screw f'', applied over the same.

p is a driving-pulley on shaft A, and G are gear-wheels connecting the cutter-shafts.

b is a rubber collar sprung into a groove formed in the hub a' of the lower cutter, and constructed of such diameter as to press elastically against the periphery of the cutter c. The latter therefore indents the same as it rotates, as shown in Fig. 10, and when the hat-brim d is inserted between the cutters tends to press the brim into the rubber, which then grasps the felt and pulls it continuously between the cutters.

d is the brim of the hat, applied to the cutting-edges; d', the hat-crown, and t t' are tables for supporting the brim of the hat at opposite sides.

e is a gage fitted to the hat-band, and provided with a foot, g, extended over the upper cutter and fitted to a guide, g', in the top of the frame F, the foot being provided with a slot, g'', Fig. 4, embracing the screw f'; and a washer and a clamp-nut, f'', are applied to the same screw to bind the foot g and clamp the gage in the required position.

e' is a screw fitted to an ear, e'', upon the foot g, and tapped in the front of the frame F to adjust the gage to and from the cutters.

h is a pressing-roller fitted within the hat-crown opposite the gage e, and mounted upon an arm, I', which is movable with a rod, J, in the bracket J', attached to the front of the frame, and K is a spring applied to the rod to press the arm and the roller h toward the gage. The bracket J' is projected from the front of the frame F beneath the cutters, and is provided with posts I I', to sustain the tables t t',

and the rod *J* is fitted loosely into the said posts, so that the arm *I'* can be moved to and from the center of the hat. A slot, *i*, Fig. 2, is formed in the bottom of the bracket *J'*, and 5 a handle, *L*, is attached to the rod *J* to move the rod and roller *h* as required.

The gage in Figs. 1 to 5, inclusive, is shown as a concave plate or bar held adjacent to the hat-band, operating by contact with the crown 10 *d'* to guide the hat-brim in a given path between the rotary cutters. With this construction the operator withdraws the roller *h* from contact with the gage *e* to the position shown in Fig. 2 by means of the handle *L*, and then 15 inserts the brim of the hat beneath the gage, as shown in Fig. 1, the tables *t t'* supporting the brim of the hat at opposite sides of the roller, and the latter pressing the band of the 20 hat firmly against the gage. The brim of the hat when in this position passes between the shearing-edges of the cutters, so that the rotation of the latter trims off a strip, as 25 at *s* in Figs. 1 and 2; the hat-brim being grasped and drawn continuously through the 30 cutters by the feeding-disk until the entire edge of the brim has been reduced to the desired width. As the gage is held rigidly at a fixed distance from the plane of the 35 cutters, it is obvious that if the gage touch as a tangent at all points of the hat-band, the brim would be trimmed off parallel with the band, or of even width all around, as shown in the trimmed section of the brim from *l* to *l'* in Fig. 2; but, as it is frequently necessary to 40 trim the brim of varying width at different parts of the crown, we have invented the following devices to render the gage operative for such purpose. Thus in Figs. 3, 4, and 5 the gage is shown faced with a leaf-spring, *m*, which is attached to the gage at its middle, 45 but sustained by set-screws *n*, inserted through the ends of the gage, and may thus be bent to a variety of curves. Its effect when bent to fit the most convex part of the band is shown 50 in Figs. 4 and 5, the gage being shown in contact with the front of the crown in Fig. 4 and with the side crown in Fig. 5. The gage obviously pushes the hat away from the cutters 55 when the side crown is presented to it by reason of the flatter curvature of the side crown, as shown in Fig. 5, and thus producing a wider brim at the sides than at the front and rear of the crown. Such increased width is 60 very desirable where a hat-curl is to be formed at the sides of the hat-brim, and the difference between the black line *l* and the dotted line *l'* in Fig. 5 shows how such difference is produced by the operation of the gage when adjusted in the manner described.

65 To adapt the gage to trim the brim wider at the front and rear of the crown, we apply to the band of the hat an auxiliary band, (shown in Figs. 8 and 9 at *O O'*.) the same being formed of india-rubber, leather, or other material, with a greater thickness at the front and rear of the crown than at the sides, so that when in contact with the gage *e* the hat-crown

will be pushed away from the cutters at the desired points, and the brim be thereby trimmed with the required variation in width at such 70 points.

To set the gage conveniently at the desired distance from the plane of the cutting-edges, we provide a scale, *q*, upon the foot *g*, and an index, *q'*, upon the frame, the divisions of 75 such scale being numbered or marked with the brim-measures of widths produced when the gage is set thereby. The screw *e'* may also be made with a thread of one-sixteenth inch pitch, and the head of the screw may be 80 provided with a scale or with a single mark corresponding to an index, *n'*, fixed upon the foot, so that the operator may be guided in turning the screw exactly one revolution.

As the brim-measures are computed in 85 eighths of an inch, it is obvious that the gage may be moved to correspond with the half-sizes by turning the screw just one revolution, and the divisions representing half-sizes may therefore be omitted from the scale *q*, to avoid 90 obscuring the larger divisions.

To conveniently retract the roller *h* with the right hand of the operator when the left hand is engaged in removing or inserting a hat in the machine, the shifting-handle may be applied back of the cutters, as shown in an alternative construction at *L'* in Figs. 1, 2, and 4. In this case the rod *J* is extended beneath and 95 past the cutters, and provided with a stud, *m*, and the lever *L'* is pivoted upon the frame at 100 *u*, and provided with a slot, *m'*, to fit over the stud, so that the operator may retract the roller by applying his right hand to the handle of the lever *L'*. The lever is shown in the required position to retract the roller in Fig. 105 2, while the roller is shown in an operative position with the lever pushed backward in Fig. 1.

It is obvious that a convex presser of any kind would operate substantially like the roller *h*, and that it is immaterial how the presser is mounted, provided it is pressed elastically toward the gage *e*, and may be moved from the same sufficiently to insert the hat.

In place of the rubber collar applied to the 115 hub of one of the cutters, an eccentric sliding collar may be applied to the face of the cutter, as shown in Figs. 6 and 7, where *D* is a screw-bolt extended from the center of the shaft *C*. *D'* is a thumb-nut applied to the end of the 120 same. *D'* is a star-shaped spring under the thumb-nut, and *b'* a circular collar slipped over the bolt and held elastically against the face of the cutter *c* by the spring. The collar is formed with a hole larger than the diameter 125 of the bolt, and is applied to the face of the cutter *c*, in a line with the cutter *a*, so as to rotate in contact with the rim of the latter. The collar is made of such diameter as, when placed concentrically upon 130 the cutter *c*, to interfere with the rim of the cutter *a*, and the latter cutter therefore pushes it into an eccentric position relative to the cutter *c*, as shown in the drawings.

When the hat-brim is applied to the cutters, the felt passes between the collar b' and the rim of the cutter a , the friction of the spring D^2 resisting the eccentric movement, which is 5 constantly produced by the rotation of the collar in contact with the felt. Such frictional resistance produced by the sliding of the collar toward the spring and the cutter c therefore produces the needed pressure of the collar 10 upon the felt to draw the same continuously into the cutters, as described above for the rubber collar.

The spring D^2 is made star-shaped, so that its several arms may press elastically upon 15 the sliding collar, and it is provided with a tongue, b^2 , fitted into a groove in the bolt, so as to rotate with the latter.

The nut D' furnishes the means of exerting more or less pressure upon the spring, and 20 thus increasing the sliding friction of the collar against the cutter c , such friction serving to produce a constant yielding pressure of the collar against the rim of the cutter a when the cutters are in operation.

25 Having thus described our improvements, it will be seen how we are able to trim or round a hat-brim of even width all around or with variations in width at the front or side of the crown, and that we secure by the combination of the yielding feeding-collar with the rotary cutter an application of the feeding motion at the exact point where the cut 30 operates. Our construction therefore enables us to round hats more exactly and uniformly than has heretofore been done.

35 We are aware that certain constructive features of our machine have been used in other machines with somewhat different functions; and we therefore disclaim the separate 40 elements of our construction, and restrict ourselves to the combinations which we have claimed, and operating in the manner described.

What we claim herein is—

- 45 1. In a hat-rounding machine, the combination, with a pair of rotary cutters, of a rubber collar affixed directly to one of the cutters and adapted to press the hat-brim adjacent to the cutter during the cutting operation.
- 50 2. In a hat-rounding machine, the combination, with means for supporting the hat-brim, of the cutter a , the yielding collar, and the cutter c , arranged to press the brim against the collar while cutting against the face of the cutter a .
- 55 3. In a hat-rounding machine, the combina-

tion, with the cutters a and c , operated as described, of the frame in the rear of the cutters, the hat-brim support at the front of the cutters, and the crown-gage attached adjustably to the frame, as and for the purpose set forth.

60 4. In a hat-rounding machine, the combination, with the cutters a and c , arranged and operated as described, of the frame arranged in the rear of the cutters, the hat-brim support at the front of the cutters, a crown-gage, arranged and operated as described, and a presser applied within the crown of the hat to press it toward the gage, as and for the purpose set forth.

65 5. In a hat-rounding machine, the combination, with rotary cutters and a crown-gage, operated as described, of a presser arranged inside the crown, as set forth, and means, substantially as described, for retracting the presser to insert the hat beneath the crown-gage, substantially as herein set forth.

70 6. In a hat-rounding machine, the combination, with rotary cutters and a crown-gage, operated as described, of a presser mounted upon a sliding bar, as described, a spring to actuate the presser, as set forth, and a handle to retract the bar and presser, as and for the purpose set forth.

75 7. The combination, with the rotary cutters and the frame arranged in the rear of the cutters, of the crown-gage provided with a foot extended over the upper cutter and fitted to a guide in the top of the frame, as described, and provided with an index corresponding with the width of the brim, substantially as and for the purpose set forth.

80 8. The combination, with the rotary cutters and the frame arranged in the rear of the cutters, of the crown-gage constructed with a foot fitted to a guide in the frame, and provided with an adjusting-screw having a thread adapted in one rotation to move the gage the required amount for a variation of half a size in the hat-crown, substantially as shown and described.

85 In testimony whereof we have hereunto set our hands, in the presence of two subscribing witnesses.
